UNITED STATES PATENT OFFICE.

CHARLES E. BEACH, OF WASHINGTON, DISTRICT OF COLUMBIA.

SUPPLEMENTAL PRESS-BASE FOR PRINTING-PLATES.

SPECIFICATION forming part of Letters Patent No. 747,845, dated December 22, 1903.

Application filed June 2, 1903. Serial No. 159,788. (No model.)

To all whom it may concern:

Be it known that I, CHARLES E. BEACH, a citizen of the United States, residing at Washington, District of Columbia, have invented 5 certain new and useful Improvements in Supplemental Press-Bases for Printing-Plates, of which the following is a specification.

This invention relates to supplementary press beds, bases, or blocks, and the object is 10 to provide a structure of this character which will hold all sizes and kinds of printing-plates at different distances apart, so that the margins between them may be regulated as desired.

15 A further object is to provide simple means for adjusting the plates to overcome the inequalities in the height of the printing-surfaces thereof, thus obviating the necessity of the usual underlays. As a result, plates of 20 any size or any number within the capacity of the press may be employed in any position desired.

The structure that at present is considered preferable is illustrated in the accompanying 25 drawings; but it will be understood that various changes may be made in the size, form, and details of construction without departing from the spirit of the invention.

In the drawings, Figure 1 is a top plan view 30 of the improved structure, showing plates in place thereon. Fig. 2 is a view in elevation of one end of the bed. Fig. 3 is a view in elevation of the opposite end, portions thereof being broken away and shown in section. 35 Fig. 4 is a vertical sectional view through the bed, taken on the line 4-4 of Fig. 1. Fig. 5 is a detail perspective view of one of the clamp-blocks located at the margins of the bed. Fig. 6 is a view in elevation of the actuating rack-bar. Fig. 7 is a detail perspective view of one of the holding-blocks inverted, and Fig. 8 is a similar view of one of the margin-fastening devices. Fig. 9 is a detail perspective view of one of the holding-blocks. 40 Fig. 10 is a view of the adjusting-screw detached.

The same reference-numerals are employed in designating similar parts throughout the several figures.

50 In the construction illustrated in the accompanying drawings a supplemental bed 10 is employed, having on its under side spaced

ribs 11, that are preferably located diagonally of the bed. (Indicated in Fig. 1.) Said bed is provided with spaced rows or series of 55 threaded openings 12, extending vertically through the same from top to bottom and being disposed between the ribs. These openings are normally closed by adjusting-screws 13, threaded into the same and having their upper ends suitably slotted, said ends or heads being so constructed that they will lie flush with the upper face of the bed. Holding devices are also employed, said devices being in the form of oblong blocks 14, the edges of 60 which are undercut, as shown at 15. These holding devices are provided with centrally-disposed openings 16, having their upper portions countersunk, and through said openings are passed fastening-screws 17, the heads of 65 which fit in the countersunk portions, while the shanks are adapted to screw into the openings 12, the adjusting-screws being first removed. Certain of these holding devices that are disposed along the margins of the bed (designated 15^a) are tapered, the thicker edges being undercut. Two of the edges of the bed are reduced in thickness to provide outstanding flanges 18, and to the outer edges of the flanges are secured by means of screws 19 70 strips 20, the upper portions of which project above said flanges and are spaced from the bed, thus forming gutters. Extending into the bed from these edges are slots 21, the lower portions of which are enlarged to provide 75 recesses 22. Spindles 23 are located longitudinally in the recesses and have their ends journaled, as shown at 24, in the strips 20 and the inner end walls of the recesses. The intermediate portions of the spindles are 80 threaded and gear-wheels 25 are attached to their outer ends, said gear-wheels being located in the gutters. Clamping-blocks 26 are 85 slidably mounted on the bed over the slots 21 and are provided with depending ears 27, 90 projecting through said slots and having threaded engagements with the spindles. The portions of the blocks projecting above the bed have their inner edges undercut, as shown at 28. In connection with these clamping devices an actuating rack-bar 29 is employed 95 which is adapted to fit in the gutters and preferably has a suitable handle 30.

The plates to be clamped are shown gener-

ally at 31, said plates having beveled edges 32. These plates are laid upon the bed 10 and can be properly adjusted as to height by means of the various adjusting-screws 12, 5 that may be located beneath them. This, it will be observed, does away with the necessity of underlays usually employed. The fastening devices are then located about the inner edges of the plates and also constitute 10 means for spacing said plates apart, so that margins of different widths can be obtained. These will be clearly evident by reference to Fig. 1, wherein the same blocks are employed for obtaining two different widths of margins, 15 the oblong shape of the blocks therefore being an important feature, as will be apparent. The fastening-blocks are held in place by screws, which are threaded into the same openings that receive the adjusting devices, 20 and therefore said devices are interchangeable, requiring openings of a single size. Those adjusting-screws which are not covered by the plates are left in place in the bed, and thus prevent the openings being filled with 25 ink, grease, and dirt. The inner and intermediate fastening devices having been properly positioned to place the plates in the desired relation the clamping-blocks are brought into engagement with the free edges 30 of said plates by revolving the spindles, this movement being accomplished by the actuating-rack already described. The result is that the plates are securely fastened in position and yet can be adjusted or removed with 35 ease and despatch. Thus it will be seen that the various objects pointed out in the preliminary part of the specification are accomplished by means that are simple, can be easily and cheaply manufactured, and applied 40 to any of the ordinary types of bed-presses.

Having thus described my invention, what I claim as new, and desire to secure by Letters Patent, is—

45 1. In a press-base for printing-plates, the combination of a bed having a multiplicity of threaded openings therein, adjusting-screws registering in said openings and filling the latter with their heads arranged to engage 50 beneath the printing-plate, and a plate-holding device including screws interchangeable

with the adjusting-screws in any of the said threaded openings.

2. In a structure of the class described, the combination with a bed having a series of 55 openings extending into the same, from its upper face, of adjusting-screws threaded into the openings and having heads of substantially the same diameter as the openings, said screws normally filling the openings with the 60 heads flush with the upper face of the bed, and plate-holding devices including screws which are constructed to be threaded into the openings when the adjusting-screws are removed. 65

3. In a press-base for printing-plates, the combination of a bed-plate having a series of spaced ribs on its under side, and a multiplicity of threaded openings piercing the same in the intervals between the ribs, and separate 70 plate-adjusting and fastening screws interchangeable in the same openings.

4. In a press-base for printing-plates, the combination of a bed-plate provided with a multiplicity of threaded openings, adjusting- 75 screws normally filling the openings, and plate-holding devices comprising rotatable oblong blocks having engaging portions at all of their edges, and fastening-screws for said blocks interchangeable with any of the ad- 80 justing-screws.

5. In a structure of the class described, the combination with a bed-plate having a plurality of openings extending into the same from its upper face, adjusting-screws thread- 85 ed into the openings and normally having their heads flush with the upper face of the bed, said screws being movable above the bed to form supports for a plate placed thereon, and plate-fastening devices comprising ob- 90 long blocks adapted to be placed upon the bed and having undercut edges and screws passed through the blocks and of proper size to engage in the openings of the bed when the adjusting-screws are removed. 95

In testimony whereof I affix my signature in presence of two witnesses.

CHARLES E. BEACH.
